UNITED STATES PATENT OFFICE.

MARY E. STREET, OF ST. LOUIS, MISSOURI.

BATHING-SUIT.

1,111,193.

Specification of Letters Patent.

Patented Sept. 22, 1914.

Application filed February 28, 1914. Serial No. 821,747.

To all whom it may concern:

Be it known that I, MARY E. STREET, citizen of the United States, residing at St. Louis, State of Missouri, have invented certain new and useful Improvements in Bathing-Suits, of which the following is a full, clear, and exact description, reference being had to the accompanying drawings, forming a part hereof.

10 My invention has relation to improvements in bathing suits; and it consists in the novel construction of suit more fully set forth in the specification and pointed out in the claims.

15 In the drawings, Figure 1 is a perspective view showing the application of my invention; Fig. 2 is a rear view of the garment, parts being broken away; Fig. 3 is an enlarged vertical cross-section on the line 3—3 20 of Fig. 2; and Fig. 4 is a horizontal cross-section of the suit, on the line 4—4 of Fig. 1.

The present invention is particularly directed to bathing suits for women (though not restricted thereto) and has for its object to provide a one-piece garment or suit which may be quickly put on and fastened, and as quickly taken off; one provided with means for imparting buoyancy to the garment by a retention of a certain amount of 25 air; one in which suitable panels are substituted for the conventional skirt, thereby reducing the weight of the garment; and one possessing further and other features the 30 advantages of which will be readily apparent from a detailed description of the invention which is as follows:

Referring to the drawings, 1 represents the blouse of the garment and 2 the conventional bloomer members or trousers which may be of any desired length, a suitable 40 waist band 3 being provided between the base of the blouse and the top of the trousers. The blouse is provided with sleeves 4 which are shortened to reach above the elbow, although the length of the sleeves 45 may be varied, said sleeve being provided with a slit 5 in the back for the comfort and free movements of the arms of the bather or swimmer. The garment is quickly fastened by means of any conventional forms 50 of fastening devices such as glove or shoe fasteners, comprising female or socket members *a* on the outside of the waist-band which are engaged by studs or male members *b* 55 on the inside of the waist-band, the number and disposition of the fastening devices be-

ing such that the garment may be adjusted to any desired fit about the waist of the bather.

Depending from the bottom edge of the 60 waist-band 3, at the front and back, and covering the split between the trouser or bloomer sections 2, 2, are panels 5, which, while imparting a skirt-like effect to the garment, reduce the weight of the garment, 65 a decided advantage over a full skirt. These panels preferably reach down to the bottom of the bloomers, although I do not wish to restrict myself to any precise length of panel. Disposed on the inside of the back 70 of the blouse is a yoke or layer 6 extending cross-wise from one arm-hole *O* to the other, the lower edge of the yoke occupying a position across the back substantially between the upper edge of the waist-band and the 75 bottoms of the arm-holes. The lower edge of the yoke is free or loose from the back of the blouse, thus forming with said back an air sack or chamber *C* in which the air is retained for a considerable length of 80 time, the confined air rendering the garment exceedingly buoyant and serving a purpose akin to a pneumatic life-preserved. In practice, the sack inflates more or less, the wet garment preventing leakage of the air 85 through the meshes thereof (see dotted showing in Fig. 3). To insure the air retention however, the back of the blouse and the yoke 6 may be made of material practically 90 impervious to air, in which event a permanent buoyancy can be imparted to the garment.

From the foregoing, it will be seen that the various advantages enumerated at the outset, are present, the garment fulfilling 95 the several objects contemplated by the invention. The garment may obviously be changed in minor details without departing from the general nature or spirit of the invention.

Having described my invention, what I claim is:—

1. A one-piece bathing suit comprising a blouse, a waist-band and trousers, front and back panels depending from the lower portion of the waist-band and covering the split between the trouser members, and fastening means on the waist-band.

2. A one-piece bathing suit comprising a blouse, sleeves therefor provided with slits in the back, a waist-band and trouser members, front and back panels depending from

- the lower edges of the waist-band and covering the split or open space between the trouser members, and fastening means on the waist-band.
- 5 3. A one-piece bathing suit comprising a blouse, a waist-band and trousers, front and back panels covering the split between the trouser members, and an air sack on the back of the blouse.
- 10 4. A one-piece bathing suit comprising a blouse, a waist-band and trousers, front and back skirt panels depending from the waist band and operating to cover the split between the trouser members, fastening means 15 on the waist-band, a yoke-piece secured to
- the inside of the back of the blouse between the arm holes and extending to a point intermediate the bottoms of the arm-holes and the upper edge of the waist-band, the lower edge of the yoke being free from the back 20 of the blouse whereby an open air sack is formed between the yoke and blouse, and sleeves on the blouse having rear slits, as set forth.

In testimony whereof I affix my signature, in presence of two witnesses.

MARY E. STREET.
